UNITED STATES PATENT OFFICE

149,356

DESIGN FOR A COMBINED PENCIL SHARPENER AND ERASER

William R. Jalof, Los Angeles, Calif.

Application March 8, 1947, Serial No. 137,462

Term of patent 14 years

(Cl. D74—1)

To all whom it may concern:

Be it known that I, William R. Jalof, a citizen of the United States and residing at Los Angeles, in the county of Los Angeles, State of California, have invented a new, original, and ornamental Design for a Combined Pencil Sharpener and Eraser, of which the following is a specification, reference being had to the accompanying drawing forming part thereof, in which:

Fig. 1 is a perspective view of a combined pencil sharpener and eraser, showing my new design,

Fig. 2 is a top plan view thereof,

Fig. 3 is a side elevation,

Fig. 4 is a view of the eraser holding end, and

Fig. 5 is a view of the pencil receiving end.

I claim:

The ornamental design for a combined pencil sharpener and eraser, substantially as shown.

WILLIAM R. JALOF.
